UNITED STATES PATENT OFFICE.

HOWARD L. KRUM, OF CHICAGO, ILLINOIS, ASSIGNOR, BY MESNE ASSIGNMENTS, TO MOKKRUM-KLEINSCHMIDT CORPORATION, OF CHICAGO, ILLINOIS, A CORPORATION OF DELAWARE.

TELEGRAPH SYSTEM.

Original application filed June 30, 1916, Serial No. 106,925. Patent No. 1,434,290, dated October 31, 1922. Divided and this application filed October 30, 1922, Serial No. 597,895. Renewed May 2, 1927.

The present application is a division of my prior application, Serial No. 106,925, filed June 30, 1916. Patent No. 1,434,290, dated October 31, 1922.

5 The invention relates to selective or automatic printing telegraphs having selective transmitting and receiving mechanisms and means for maintaining the receiving mechanism at one station in synchronism with the 10 transmitting switch mechanism at another station.

The present invention seeks to provide a selective telegraph system of this sort in which improved means are employed in effecting the synchronous operation of the 15 transmitter and receiver mechanisms at the connected stations.

To this end I employ a novel normally closed line circuit in association with a relay 20 which responds to the opening and closing of the circuit to effect control of the receiving distributing mechanism and the operation of the signal receiving magnets.

The various features and objects of the 25 invention will be more fully understood upon reference to the following detail description taken in connection with the accompanying drawing, while the scope of the invention will be particularly pointed out in the appended claims.

The figure of the drawing is a diagram of 30 circuits arranged according to the present invention and connecting two stations, one a transmitting station and the other a receiving station.

The receiver switch mechanism which I employ is fully described in the aforesaid parent case, but certain of its parts are shown in the drawing. These include a 40 rotating switch arm *a* and a circular series of cooperating contacts fixed to an insulating disk *A*. Preferably, the disk is arranged so that the contacts may be adjusted, as fully pointed out in the aforesaid case.

45 The switch arm *a* is mounted upon a sleeve 17 which, in turn, is mounted upon a shaft 18. The fit is loose and, consequently, the sleeve 17 held stationary during the rotation of the shaft 18. The latter extends through 50 a central opening in the disk *A*. As pointed out more fully in the parent case, the shaft 18 is continuously driven by a motor, the

speed of which is maintained constant. The sleeve 17 is driven by the shaft 18 through the medium of a yielding friction device. 55

For this purpose the shaft has secured to it a disk-like portion 25, having a laterally projecting edge flange 26, and a hub 27 fixed to the adjacent end of the sleeve 17 is provided with a series of curved springs 28, 60 each of which engages the inner face of the flange 26 through an arc of considerable size. The friction disk 25 and flange 26 are preferably formed of cast iron and the springs of hardened steel. The inner ends 65 of the latter are suitably secured to the hub 27 and at their outer ends are pressed snugly against the inner face of the flange 26. These parts afford a secure connection between the shaft and the sleeve so that the 70 latter is properly driven. But the connection is such that the sleeve and receiver switch carried thereby can be arrested, since the connection between the sleeve and the shaft afforded by the springs 28 and the 75 friction disk will yield or slip. The space within the flange 26 is ordinarily enclosed and filled with a suitable lubricant to prevent undue wear of the springs 28.

A disk 31 fixed to the sleeve 17 is provided with a shoulder 32 which normally engages a stop arm 33. The latter constitutes the armature of a trip magnet *C* and is pivotally mounted on the upper end of the frame *C'* of this magnet. A spring 34 extending between the outer end of the stop arm 33 and a pin 35 on the frame *C'* holds the inner end of the arm against the periphery of the stop disk 31. 80

By this means the sleeve 17 and switch 90 arm *a* are held against movement, but when the trip magnet *C* is energized the stop arm 33 is disengaged from the shoulder 32. The friction connection between the shaft and sleeve is then effective to rotate the sleeve 95 and switch arm through a single revolution whereupon they are again arrested by the engagement of the shoulder 32 with the stop arm 33. The friction drive connection set forth operates effectively to quickly pick 100 up and rotate the switch arm as soon as the trip magnet is energized.

The sleeve 17 also preferably carries an insulated cam *d* which is arranged to operate

a switch arm D. The latter is suitably spring-pressed in a direction to bring it into engagement with contact 39 when not interfered with by the cam d. The latter is 5 shown as provided with a recess 43 and when the parts are in the position shown, with the sleeve held against movement by the arm 33, the upper bent end of the switch arm D projects within the recess 43 so that the contact 39 is engaged by the switch arm D. But during the greater part of the revolution of the sleeve 17 the cam d holds these contacts out of engagement.

The receiver switch mechanism above described may be combined with a transmitter switch mechanism into a single station instrument, as fully set forth in the aforesaid parent case.

Shaft 50 forms the driving element of the transmitter switch mechanism which comprises a rotating switch arm e, and an annular contact disk E. The arrangement of the disk E is similar to that of the receiver disk A, except that the transmitter disk 20 contacts are not adjustably mounted. Like the receiver switch arm a, the transmitter switch arm e is mounted on a sleeve 17 and is connected to its driving shaft 50 through a similar yielding friction connection, and 25 the sleeve is provided with a like controlling disk 31 and stop arm 33, the stop arm of the transmitter switch mechanism being controlled by a trip magnet F.

The sleeve 17 of the transmitter switch mechanism is also provided with a cam g, 35 which controls a switch G similar in construction to the switch D previously described, but the cam g is reduced in diameter through the greater portion of its periphery, 40 being provided with a lug 51. Thus the switch G is in closed position through the greater portion of the revolution of the transmitter switch, but is momentarily opened just before this switch completes a 45 revolution.

Each transmitter and receiver disk is provided with six contacts. A set of selecting switches h serves to variably connect contacts 1, 2, 3, 4 and 5 of the transmitter disk 50 to a source of current to thereby determine the combinations of impulses imparted to the line as the transmitter switch arm e passes over these contacts. Preferably, the 55 signals are represented by permutations of five current and no-current impulses, and the switches h serve to variably connect and disconnect the line conductor 92 to and from the battery H², the selecting switches having normally disengaged contacts only. The 60 selecting switches h are directly connected to the contacts 1, 2, 3, 4 and 5 of the transmitter disk by a set of conductors 54, and the transmitter switch arm e is connected directly to the line circuit. The normal or 65 rest position of the transmitter switch is in

engagement with contact 6 which is permanently connected to the battery and the switch itself is connected to the line conductor 92, as just stated, so that current is normally maintained upon the line.

The line conductor 92 extends through a neutral relay W at the distant station which normally holds its spring-held tongue against its front contact, this contact being connected by conductor 93 to the receiver 75 switch arm a, and the tongue being connected to the local battery L by the conductor 94. The space is left between the contacts 6 and 1 of the transmitter disk so that no current is on the line as the switch arm 80 e passes between them.

A set of branch conductors 62 connects the contacts 1, 2, 3, 4 and 5 of the receiver disk to a set of five selecting relays or magnets M¹, M², M³, M⁴ and M⁵, and a conductor 63 connects the contact 6 of the receiver disk to an underlocking or releasing magnet N. Magnet N operates a normally closed switch n which is connected to the local battery L by a conductor 64, and the contact of this switch is connected by a conductor 65 to the contacts of a series of normally open locking switches m that are operated, respectively, by the magnets M¹, M², M³, M⁴ and M⁵, and are connected to the conductors 62 that lead to the coils of these magnets. The arrangement is such that when any of the selecting magnets is operated, it will remain connected to the local battery until the underlocking switch n is opened.

When the line circuit is opened by reason of the transmitter switch arm e passing between contacts 6 and 1, line relay W is de-energized and its tongue w is drawn by its spring into engagement with its back contact and closes the circuit from the local battery L by conductor 94, and the switch tongue w, conductor 95, switch D, and conductor 96 to the trip magnet C. The latter is thus actuated at the beginning of each 100 transmitted signal. The coils of the magnet C, N, M¹, M², M³, M⁴ and M⁵ are grounded or connected by a suitable return wire to the local battery L.

The transmitter selecting switches h are variably operated by a set of finger keys, one of which is shown at 68, and which are arranged like the keys in an ordinary typewriter. The keys are provided with lugs 69, these lugs being so arranged that the depression of each key will operate a particular combination of the selecting switches which correspond to the character represented by the key. Each finger key of the transmitter is also arranged to operate a switch h' which is connected to the coil of the trip magnet F and also to the coil of the magnet P. Preferably the cut-out switch G is arranged in the circuit of the trip magnet F. As shown in the diagram 110 115 120 125 130

the switch h' is connected by a conductor 70 to the coil of the magnet P, and the latter is connected by conductor 71 to the switch G, the contact of which is connected to the 5 coil of the magnet F by a conductor 72. Switch h' has only one normally disengaged contact which is connected by a conductor 73 to the battery H^2 . One terminal of the magnet F is grounded or connected by a 10 return wire to the battery H^2 .

Each finger key 68 is provided with a projecting lug 74 which is arranged to cooperate with a locking device 75 on the armature p of the locking magnet P.

15 When a finger key is depressed, certain of the switches h are shifted so that as the transmitter switch arm e passes over the contacts 1, 2, 3, 4 and 5, a permutation of current and no-current impulses, corresponding to the depressed key, is transmitted to the line. The key also shifts the switch h' so that current flows from battery H^2 by conductor 73, switch h' , conductor 70, through magnet P, thence by conductor 71, 20 switch G and conductor 72 through the trip magnet F. Magnet F is thus energized to permit the operation of the transmitter switch e , and magnet P is also energized to operate the lock device 75. This lock device holds down the shifted key and prevents the premature operation of the other keys. Just before the transmitter switch completes its revolution the cam g opens the switch G and the magnets P and F are 25 deenergized. The transmitter switch is arrested at the end of a revolution and after it has passed over a number of contacts sufficient to transmit the combination of impulses corresponding to a single character. 30 It should be noted, however, that since the switch G is opened to release the locking device 75 before the rotary transmitter switch member reaches its normal position, messages may be rapidly transmitted without appreciable pauses between the signals.

35 The line circuit is normally closed and the tongue w of the line relay W at the distant station is held against its normally engaged or front contact. The selecting impulses of each signal are preceded by a uniform opening of the line circuit at the transmitter as the switch arm e passes from the contact 40 to contact 1 of the transmitter disk. This starting interval will cause the tongue w of the line relay W to engage its back contact and circuit may then be traced from battery to the trip magnet C as previously noted. The stop arm 33 is then released and the receiver switch at once commences to rotate 45 over the contacts of the receiver disk. As soon as this occurs, cam d opens the switch D and the magnet C is deenergized so that the stop arm is in position to arrest the receiver at the end of a single revolution. 50 This switch is connected to the back con-

tact of the switch tongue w and operates in proper phase relation with the transmitter switch at the distant station so that the magnets M^1 , M^2 , M^3 , M^4 , and M^5 are variably operated in accordance with the permutations of impulses; that is to say, if the selected impulse is a current impulse the switch tongue w will be held against its front contact as the receiver switch a passes over contact 1 and magnet M' will be operated. If 55 the first selecting impulse is a no-current impulse, the circuit of the magnet M' will not be closed when the switch arm a passes over contact 1, since at this time the relay switch tongue w will be against its back contact. 60 In a similar manner the other magnets M^2 , M^3 , M^4 , and M^5 , are variably operated in accordance with the different permutations of five currents and no-current impulses.

Whenever one of the magnets is operated, 65 its switch m closes a circuit from battery L through conductor 64, normally closed switch n , conductor 65, switch m , and conductor 62, through the coils of the magnet which thus remains energized, until the unlocking or releasing magnet N is energized. This occurs when the receiver switch passes over contact 6, since at that time the transmitter switch at the distant station engages 70 its contact 6, and a current impulse passes over the line during a spacing interval at the end of each signal and holds the switch tongue relay w against its tongue contact. Thus when any signal is completed, the transmitter and receivers switch mechanisms 75 and the selecting magnets M^1 , M^2 , M^3 , M^4 , and M^5 , are restored to normal condition ready for the next signal. The variable operation of these selecting magnets can be 80 employed, as will be readily understood, to operate a suitable printing instrument.

The friction clutch device for operating the receiver switch is such that the latter picks up quickly and commences to operate as soon as the no-current starting impulse which precedes the selecting impulses of each signal is received, to thereby operate the trip magnet C. It should be noted that the members of this friction clutch or coupling 85 are constantly engaged and slip past each other when the stop arm 33 engages the shoulder of the disk 31. The parts of the frictional connection, however, pick up and operate the receiver switch as soon as the trip magnet is energized.

The shaft 18 of the receiver switch is driven somewhat faster than the shaft 50 of the transmitter switch at the distant station. But as the receiver switch is arrested at the completion of each signal it is operated in proper synchronism with the transmitter switch. Preferably, as shown, the contacts of the receiver disk are spaced farther apart than the contacts of the transmitter disk, 90 except for the space between contacts 6 and 95 100

1 upon the transmitter disk, so that the receiver switch arm can run faster and be arrested at the end of each signal when the transmitter is rapidly operated without appreciable pauses between the signals. Obviously, the difference in the relative angular spacing of the receiver and transmitter contacts should accord with and thus compensate for the relative difference in speeds 10 at which the respective contact arms are usually operated.

By accelerating the operation of the receiver switch arm relatively to that of the transmitter at the distant station, or having 15 its period of operation relatively shorter, the receiver switch arm will be invariably arrested in normal position at the end of each signal and again started in proper phase with the starting no-current impulse received from the distant station at the beginning 20 of each signal. It should also be noted that not only is the angular spacing of the contacts of the receiver disk relatively greater than that of the transmitter disk but the receiver contacts are also considerably smaller, and that by adjusting the receiver disk in the manner more particularly pointed out in the parent case, the relation between its contacts and the normally arrested position 25 of the receiver switch arm can be so adjusted that the latter can be started and caused to register with the contacts during the mid-portions only of the selecting impulses or intervals of the received signals. Since the 30 operation of the rotary transmitter member is locally controlled independently of the line conditions and by its movement during each signal period establishes all the changes in the line conditions, including the starting intervals, the receiver contacts need only be adjusted relatively to the normal rest position of the rotary receiver switch member to take care of variations in the time operation 35 of its own starting means. Furthermore, no great frequency of speed adjustment is required to maintain the receiver member in proper operative relation with the transmitter member at the distant station. Thus the speed of the shaft 18 which 40 operates the receiver can vary as much as 10 per cent or 15 per cent without affecting the proper operation.

This is a particular advantage in lines having receiver mechanisms at a number of 45 different stations all acting in response to a transmitter at a single station, since it is not necessary to accurately adjust or attune the receiver at each station in accordance with the speed of the transmitter. Where 50 each station is provided with a combined transmitter and receiver, as explained in my parent case, satisfactory operation may be obtained. In the particular form illustrated in said parent case the receiver shaft 55 rotates considerably faster than the trans-

mitter shaft and in the ratio of 39 revolutions for each 36 revolutions of the transmitter shaft. If two such instruments are employed at connecting stations and the station motors are operated at substantially the 70 same speed, the rotary receiver member at each station will be driven faster than the transmitter member at the distant station and, by means of the start and stop clutch individual thereto can be brought into proper 75 phase relation with the transmitter at the distant station between successive signals. While the rotary transmitter and receiver members of a combined station instrument are driven from a common motor, separate 80 individual start and stop clutches are provided for arresting the same in normal position. With this arrangement the transmitter clutch can be and is controlled locally and independently of the line impulses, while 85 the receiver clutch is controlled by the first non-current impulse imparted to the line by the movement of the distant transmitter from normal position.

It is obvious that numerous changes may 90 be made in the details set forth without departure from the essentials of the invention as defined in the claims.

I claim as my invention:

1. A telegraph system including a line 95 conductor and a source of current in series therewith, a set of selectable contacts arranged to close or open said line circuit dependent upon their selected or non-selected condition, means for selectively operating said contacts, a distributor mechanism movable from a normal position to successively bring said contacts into series relation with the line, a relay in circuit with said line responsive to the opening and closing thereof, a local circuit including a second distributor mechanism under the control of said relay, and means dependent upon the movement of 100 said first mentioned distributor mechanism from its normal position to initially open 105 said line circuit to initiate the operation of said second distributor mechanism.

2. A telegraph system including a line 110 conductor and a source of current in series therewith, a set of selectable contacts arranged to close or to open said line circuit depending upon their selected or non-select- 115 ed condition, means for selectively operat- 120 ing said contacts, a distributor mechanism movable from a normal position to success- 125 sively bring said contacts into series rela- tion with the line, a relay in circuit with said line responsive to each opening and closing thereof, a local circuit including a second distributor mechanism under the control of said relay, means dependent upon the move- 130 ment of said first mentioned distributor mechanism from its normal position and invariably operating to initially open said line circuit to initially operate said relay, and 135

means responding to the initial operation of said relay to initiate the operation of said second distributor mechanism.

3. A telegraph system including a line 5 conductor, a source of current, a distributor mechanism having a series of contacts and operative to start from a closed initial position to initially open circuit and then successively close circuit through said contacts, a 10 plurality of branch circuits connected to said contacts, one of said branch circuits connecting current to said line conductor through said distributor mechanism in its initial position, circuit-closing mechanism 15 for selectively connecting current to said line conductor through other of said branch circuits, means under the control of said circuit-closing mechanism to initiate the operation of said distributor mechanism, a relay 20 in circuit with said line conductor and responsive to the opening and closing thereof, and a local circuit including a second distributor mechanism under the control of said relay.

4. A telegraph system including a line conductor, a source of current, transmitting distributor mechanism and receiving distributor mechanism associated with said line conductor, each distributor mechanism comprising a series of contacts and means movable from a normal position to successively close said contacts, means for causing said distributor mechanisms to complete their cycles, the receiving mechanism slightly 35 sooner than the transmitting mechanism, means operative to stop said mechanisms in their normal positions, said distributor contacts operating uniformly in the normal position thereof to connect said source of current to said line conductor, a relay in circuit with said line conductor and responsive to the opening and closing thereof, means responsive to the initial de-energization of said relay to start said receiving mechanism, 40 and transmitter means for starting said transmitting mechanism to cause the same to open said line conductor circuit to de-energize said relay.

5. A telegraph system including a line 50 conductor, a source of current, associated transmitting and receiving distributor mechanism associated with said line conductor, each distributor mechanism comprising a series of contacts and means movable 55 from a normal position to successively close said contacts, means for causing said receiving mechanism to complete its cycle slightly sooner than said transmitting mechanism, a connection for supplying current to said line conductor through said transmitting mechanism in its normal position, said receiving mechanism being on open circuit in its starting position, the mid-contact closing positions of the receiving mechanism being equally spaced angu-

larly and the like positions of the transmitting mechanism being equally spaced angularly except the first space following the normal position, said space being greater than the others, transmitting means for 70 starting said transmitting mechanism from its normal position, means responsive to the resulting open circuit condition of the line conductor to start said receiving mechanism from its normal position, transmitting 75 means for variously connecting current to the transmitting contacts and thence to the line conductor, and receiving means for correspondingly receiving the transmitted impulses from the line conductor through the 80 receiving contacts.

6. In a telegraph system, a line conductor, current supply, means for variously connecting said supply to said conductor, a relay 85 in circuit with said conductor and responsive to the opening and closing thereof, a receiving distributor having a conductor connected to said supply whenever said relay is energized and having also a series of distributing contacts adapted to be placed successively in circuit with said conductor, selective receiving elector-magnets in circuit with said contacts, electro-magnetic starting means for said receiving distributor, a starting circuit for said starting means closed at one 90 point whenever said relay is de-energized, and contacts responsive to the movement of said distributor to control said starting circuit at another point.

7. A telegraph system including a line conductor and a source of current in series therewith, a set of selectors, a transmitting distributor mechanism movable from a normal position to successively co-operate with said selectors and thereby variably open and close the line, a magnet in circuit with the line and responsive to the opening and closing thereof, and a receiving distributor mechanism under the control of said magnet, said transmitting distributor mechanism having means dependent upon the movement thereof from its normal position to initially open the line to de-energize said magnet and initiate the operation of the receiving distributor mechanism.

8. In a start-stop telegraph system employing a definite interval code, the combination of a line circuit, a set of transmitting selectors, a co-operating distributor having contact means normally holding the line closed and adapted, upon the movement of the distributor from a normal position, to invariably open the line at the beginning of each signal, thereafter variably open and close the line in accordance with the setting of said selectors and invariably restore the line to normal at the end of each signal, and a receiving distributor initiated in operation by the opening of the line at the beginning of each signal.

9. In a start-stop telegraph system employing a definite interval code, the combination of a line circuit, a set of transmitting selectors, a rotary distributor member and cooperating line-controlling, contact means adapted, upon the initial movement of the distributor member, to open the line during the starting interval of each signal and thereafter variably open and close the line during the selecting signal intervals in accordance with the setting of said selectors, a receiving distributor initiated in operation by the opening of the line at the beginning of each signal and stop devices

10 for arresting said distributors at the ends of the signals with said line controlling contact means in closed condition.

11. In a telegraph system employing a definite interval code, sets of transmitting and receiving selectors operable in different combinations in accordance with the signals sent and received, start-stop rotatable distributors cooperating therewith, a line closed in the normal position of said distributors, means for starting the transmitting distributor into rotation, means controlled solely by the movement of the transmitting distributor for opening the line, and means responsive to such opening of the line for starting the receiving distributor into rotation.

12. In a telegraph system employing a definite interval code, sets of transmitting and receiving selectors operable in different combinations in accordance with the signals sent and received, start-stop rotatable distributors cooperating with said sets of selectors, a line normally closed through said transmitting distributor, means for starting the latter distributor into rotation, means controlled by the subsequent movement of the transmitting distributor for initially opening the line, and means responsive to such opening of the line for starting the receiving distributor into rotation.

13. In a telegraph system employing definite interval code signals, a line circuit, a start-stop transmitting distributor normally holding the line closed and adapted by its movement from a normal position to open the line during the starting interval of a signal, a receiving distributor initiated in operation by such opening of the line, and corresponding sets of transmitting and receiving selectors associated in order with the line by the continued movement of said distributors during the selecting intervals of the signals.

14. In a start-stop telegraph system employing definite interval code signals, sets of transmitting and receiving selectors operable in different combinations in accordance with the signals sent and received, cooperating rotatable distributors having normal positions of rest, character key levers for conditioning said transmitting selectors and for starting the cooperating distributor, line controlling contact means for holding the line closed in the normal position of said transmitting distributor and operative upon the movement thereof from normal during each signal period to initially open the line, and means responsive to such opening of the line to start said receiving distributor.

15. A start-stop telegraph system employing definite interval code signals, sets of transmitting and receiving selectors operable in different combinations in accordance with the signals sent and received, cooperating rotatable distributors having a normal position for holding the line closed and a series of off-normal positions corresponding to the signal intervals and through which it is movable to thereby open the line during the starting interval of each signal and variably condition the line under control of said transmitting selectors during the selecting intervals, and electro-magnetic means responsive to the starting intervals for initiating said receiving distributor and to the selecting interval to control its selector conditioning operations.

16. A start-stop telegraph system employing definite interval code signals, start-stop rotatable distributors adapted to be continuously advanced during each signal period, stop devices for arresting said distributors in normal positions, line controlling contact means for holding the line closed in the normal position of said transmitting distributor, and operative upon the movement thereof from normal to initially open the line during the starting intervals of the signals, means responsive to such starting line condition for releasing said receiver stop device, sets of selectors associated in order with the line by the continued movement of said distributors during the selecting signal intervals and means for locally controlling the transmitter stop devices and for conditioning the transmitter selectors.

17. A start-stop telegraph system employing definite interval code signals, sets of transmitting and receiving selectors operable in different combinations in accordance with the signals sent and received, cooperating rotatable distributors having normal positions of rest, character key levers for conditioning said transmitting selectors and for starting the cooperating distributor, line controlling contact means for holding the line closed in the normal position of said transmitting distributor and operative upon the movement thereof from normal during each signal period to initially open the line, and means responsive to such opening of the line to start said receiving distributor.

18. A start-stop telegraph system employing definite interval code signals, sets of

- transmitting and receiving selectors operable in different combinations in accordance with the signals sent and received, cooperating rotatable distributors adapted to be continuously advanced during each signal period, stop devices for arresting the same in normal positions, key levers for releasing the transmitter stop devices and for conditioning the transmitting selectors, contact means for holding the line closed in the normal position of said transmitting distributor and operative, upon the release of the stop device thereof and its subsequent movement from normal to initially open the line during the starting interval of the signal, thereafter variably open and close the line in accordance with the condition of said selectors during the selecting intervals, and restore the line to normal closed condition for at least a definite interval at the end of such signal, and means for releasing the stop device of the receiving distributor and for controlling its operation in response to the uniform opening and the varied opening and closing of the line during the starting and selecting intervals respectively.
18. In a start-stop telegraph system employing a definite interval code, a line circuit, a set of contacts, controlling selectors therefor, a start-stop rotatable distributor, said contacts holding the line closed in the normal position of said distributor, and adapted, upon the movement thereof from normal to initially open the line, thereafter, upon the continued movement of the distributor, to variably open and close the line in accordance with the condition of said selectors, a magnet in said line and responsive to the opening and closing thereof, and start-stop distributing and selecting receiver mechanism controlled by said magnet and initiated in operation upon the de-energization thereof in response to the initial opening of the line effected by the movement from normal of said transmitting distributor.
19. In a start-stop telegraph system employing definite interval code signals, a normally closed line circuit connecting two stations, transmitting contacts and a receiver magnet interposed in series in said line circuit, start-stop rotatable distributor members and corresponding sets of selectors associated respectively with said contacts and said magnet, means for conditioning said selectors and for starting said transmitting member, said contacts being controlled by the subsequent movement from normal of said transmitting member to impart an open line starting condition followed by a varied open and closed line selecting conditions in accordance with the condition of the corresponding selectors, and means controlled by said magnet for starting the receiving member in response to the open line starting conditions and for cooperating therewith to position the corresponding selectors in response to the varied open and closed line selecting conditions.
20. In a start-stop telegraph system employing definite interval code signals, a normally closed line circuit, rotatable, start-stop, transmitting and receiving distributors, sets of selectors individual to said distributors, means for continuously advancing the distributors during each signal period through a series of positions to associate the corresponding selectors in order with the line during the selecting intervals, stop devices for arresting said distributors in normal position, the operating positions of said receiver member being angularly spaced further apart than the corresponding positions of said transmitter member to permit the former to be driven at a relatively greater angular speed, means for controlling said transmitting stop device and the corresponding selectors independently of line conditions, means controlled by the movement of the transmitting distributor during each signal period for opening the line during the starting interval of the signal, and means responsive to such open line condition for releasing the receiver stop device.
21. In a start-stop telegraph system employing definite interval code signals, a line circuit, a start-stop transmitting distributor normally holding the line closed and adapted, by its movement from a normal position and during each signal period, to establish an open line condition during the starting intervals of a signal followed by varied open and closed line conditions during the selecting intervals of the signal, a start-stop receiving distributor, a set of selectors controlled thereby and means for starting said receiving distributor in response to the open line starting conditions and for changing the normal position of said selectors in response to the closed line selecting conditions.

HOWARD L. KRUM.
